UNITED STATES PATENT OFFICE.

RALPH P. THOMPSON AND WILLIAM S. THOMPSON, OF LEIPSIC, OHIO, ASSIGNEES OF
ONE-THIRD TO OLIVER P. EDWARDS, OF LEIPSIC, OHIO.

AUTOMOBILE.

1,072,791.

Specification of Letters Patent. Patented Sept. 9, 1913.

Application filed October 10, 1912. Serial No. 724,979.

To all whom it may concern:

Be it known that we, RALPH P. THOMPSON and WILLIAM S. THOMPSON, citizens of the United States, residing at Leipsic, county of Putnam, and State of Ohio, have invented certain new and useful Improvements in Automobiles, of which the following is a specification.

Our invention relates to the spring suspension for automobiles.

The object of our invention is to provide efficient means for absorbing shocks to the road wheels, thereby making the car more easy riding.

A further object is to separate the spring element into sets of members, each set acting in series, but in which a difference exists between the members of each set in the time of compression and recoil, for the purpose of causing the spring movement to have the nature of a series of pulsations, out of synchronism with each other, and therefore causing to be absorbed within the spring element itself, vibrations that would otherwise be transmitted to the car frame. We accomplish this by the use of the slow acting friction retarded leaf spring of common construction, and combining in action with it, the quick acting coiled spring, together with devices which render the mechanism efficient and durable.

In the accompanying drawings, which form a part of these specifications, Figure 1 shows the front view of an automobile equipped with our spring suspension. Fig. 2 is a perspective in outline of the end of the leaf spring, together with the sliding hanger and a portion of the axle. Fig. 3 is a section in detail of the spring hanger, its slide, its supporting spring, and also showing the method of its attachment to the axle. Fig. 4 is a detail in perspective, of the rear spring suspension.

In Fig. 1 the front cross spring A is attached at either end by means of the link B and B to the spring hangers C and C. The guides D and D are bolted to the axle E, and extend upward through the hangers C and C, and terminate in a suitable stop for limiting the upward movement of the hangers C and C.

In Fig. 3 a bearing washer F on the guide D acts as a bearing to assure the alinement of the hanger C in its vertical movement.

The bearing washer F also serves as a support for the coiled spring G. A sliding collar H rests upon the top of the spring G within the hanger C. The main portion of the hanger C is cylindrical in form and adapted to inclose the spring G. The guide D extends through an opening in the top of the hanger C, and is provided with a suitable stop for confining the hanger C within the proper limit of its upward movement. The lower end of the collar H, upon which the hanger C rests, is adapted to come in contact with the washer F in confining the hanger C within the proper limit of its downward movement. A lug I, Fig. 3, on the hanger C is adapted to support the end of the spring A. Fig. 2 shows link B supporting the spring A, a swinging movement of the link B acting to compensate for the elongation of the leaf spring under pressure.

Fig. 4 shows in detail the method of attaching the suspension to the rear axle. The guide D is attached to the axle flange J, which brings the guide D close to the rear wheel, thus permitting the use of the greatest possible length of leaf spring K within the dimension of the distance between the rear wheels.

The action which takes place in our spring suspension when the vehicle is in motion is as follows:—Shock to the road wheel is absorbed more rapidly by the quick acting coiled spring than by the slow acting friction restrained leaf spring. The result is that shock to the road wheel is first absorbed by the coiled spring, and therefrom is transmitted to the body of the car and the occupants through the slow acting leaf spring. As the compression and recoil of the leaf spring is not synchronous with that of the coiled spring the recoil of the coiled spring begins to take place before the full effect of shock to the road wheel can be transmitted through the leaf spring to the body of the car. This see-sawing action, as it were, between the quick acting coiled spring and the slow acting leaf spring causes a large portion of the effect from vibration to be nullified by the action of one and reaction of the other of these springs taking place simultaneously, thus absorbing within the spring element the sharper vibrations, thereby making the car more easy riding.

Having thus fully described our invention we desire to secure Letters Patent upon the following claims:

1. In automobile construction, the combination of a non-rotating axle for the ground wheels, of pins or slides attached to and upwardly projecting from said axle, sliding members for said upwardly projecting pins or slides, and a coiled spring interposed between the axle and the sliding member, leaf springs arranged transversely of the car and above the axle and attached at their middle portion to the chassis frame and linked at their outer ends to the sliding members.
- 10 2. In automobile construction, the combination with the axle of the ground wheels, of stems attached thereto and upwardly projecting therefrom, the said stems acting as guides for the vertical movement of enlarged sleeves fitted through an opening in their top to said stems, coiled springs surrounding said stems, said coiled springs being inclosed within said sleeves and adapted to support their downward thrust, shoulders 25 on said stems upon which said coiled springs rest, and leaf springs supporting the chassis frame in their mid-length with their outer ends attached to said sleeves, all as substantially shown and described.
- 30 3. In automobile construction, wherein

coiled springs are used auxiliary to leaf springs for absorbing shock to the road wheels, the combination of upright stanchions with the axle of the ground wheels, said stanchions being attached to the outer ends of said axle, leaf springs extending above the axle and between the stanchions, and supporting the chassis frame, the said stanchions being adapted to limit the end motion of the leaf springs and thereby prevent side sway of the chassis frame, hangers for the outer ends of said leaf springs, said hangers having a vertical movement and being guided therein by said stanchions, and coiled springs interposed between said leaf 45 spring hangers and said axle of the ground wheels.

4. In an automobile, the combination with a leaf spring, a stationary guide on the axle flange adjacent to the rear brake drum and a sliding hanger adapted to slide on the said stationary guide, a coiled spring adapted to yieldably support said hanger, the said hanger being adapted to carry the end of the leaf spring.
